UNITED STATES PATENT OFFICE

159,817

AUTOMOBILE HOOD VENTILATOR GRILLE

Burdette R. Lewis and John L. Slocum,
Rochester, Mich.

Application September 19, 1949, Serial No. 5,085

Term of patent 3½ years

(Cl. D14—18)

To all whom it may concern:

Be it known that we, Burdette R. Lewis and John L. Slocum, citizens of the United States of America, residing at Rochester, Oakland County, Michigan, have invented a new, original, and ornamental Design for an Automobile Hood Ventilator Grille, of which the following is a specification, reference being had therein to the accompanying drawing, forming a part thereof, wherein:

Figure 1 is a front elevation of the automobile hood ventilator grille.

Figure 2 is a plan view of the grille shown in Figure 1.

We claim:

The ornamental design for an automobile hood ventilator grille, substantially as shown.

BURDETTE R. LEWIS.
JOHN L. SLOCUM.
